UNITED STATES PATENT OFFICE.

FRANCIS E. TURNER, OF CRESCENT CITY, CALIFORNIA.

SAFETY DEVICE FOR ENGINE CRANKING.

Application filed January 29, 1923. Serial No. 615,560.

To all whom it may concern:

Be it known that I, FRANCIS E. TURNER, a citizen of the United States, residing at Crescent City, county of Del Norte, State of California, have invented certain new and useful Improvements in Safety Devices for Engine Cranking; and I do declare the following to be a full, clear, and exact description of the same, reference being had 10 to the accompanying drawings, and to the characters of reference marked thereon, which form a part of this application.

This invention relates to improvements in safety devices for use in connection with the 15 cranking of gas engines by hand, an operation which must still be done with the engines of most automobiles of a certain popular make.

The principal object of my invention is to 20 provide a means for preventing a reverse rotation from the normal of the crankshaft of the engine, due to what is commonly known as backfiring, from being imparted to the cranking handle, which is of course in 25 operative connection with the crankshaft during the cranking operation.

Such a sudden reversal of movement as takes place with a backfire, if transmitted to the cranking handle, is very often the cause 30 of broken arms and other accidents, and the purpose of my device is to eliminate such unfortunate occurrences.

Another object of my invention is to provide a device for the purpose which may be 35 very easily applied to the car, with only the alteration of a single original part or its replacement by another made especially, being necessary.

A further object of the invention is to 40 produce a simple and inexpensive device and yet one which will be exceedingly effective for the purposes for which it is designed.

These objects I accomplish by means of such structure and relative arrangement of 45 parts as will fully appear by a perusal of the following specification and claims.

In the drawings similar characters of reference indicate corresponding parts in the several views.

Fig. 1 is a fragmentary outline of the 50 front of an automobile, showing my improved safety device installed thereon.

Fig. 2 is an enlarged sectional elevation 55 of the device and cranking apparatus, detached and showing the same in the normal cranking position.

Fig. 3 is a similar view, showing the positioning of the parts after a "kick-back" of the shaft has taken place.

Referring now more particularly to the 60 characters of reference on the drawings, the numeral 1 denotes the usual transverse spring-supporting member of the car, which supports the front spring 2, U-clips 3 being employed to bind the spring and support 65 together, the clips also securing a bearing member 4 in which the cranking shaft 5 is slidably and turnably journaled.

This shaft as usual, carries on its inner 70 end a notched member 6 adapted to be placed into detachable engagement with a transverse pin 7 on the outer end of the engine crank shaft 8.

The outer end of the shaft 5 is threaded 75 righthand for a certain distance as shown at 9, and threaded onto this portion is a ratchet wheel 10 engaged by a pawl 11 pivoted on a plate 12 mounted in connection with the member 4 and one of the clips 3, the ratchets and pawl being so disposed that 80 the wheel may turn freely in a clockwise direction but is held from rotation in the opposite direction.

The usual spring 13 is placed about the 85 shaft between the members 4 and 10, and acts to move the shaft 5 away from the shaft 8.

Placed snugly on said shaft 5 outwardly of the member 10 is a thin narrow ring 14 and outwardly of the ring the upper end 15 of the cranking-handle member 17 is 90 threaded on to the shaft.

A retaining nut 17 is screwed on to the outer end of said shaft 5, being held against movement by any suitable means, this nut acting to prevent removal of the handle 95 member.

In the operative positions of the parts the handle member 15 is snug against the outer nut 17, the ring 14 is snug against the opposite face of the handle member, while the ratchet wheel 10 is snug against the opposite face of the ring, leaving a certain number of the threads 9 unoccupied beyond the wheel 10, or toward the bearing 4.

If then the handle is rotated in the customary clockwise or right hand direction, its tendency is to move along the shaft, following the threads. This, however, it cannot do owing to the member 10 in its path of movement, this member, besides 105 being a ratchet wheel, is in effect a lock or stop nut, keeping the handle member in 110

a definite longitudinal position on the shaft.

If however the member 15 abutted directly against the member 10, a seal or bind between the two would be had which, in the absence of anything holding the member 10 stationary, would cause the latter to move along the shaft, following the threads along with the member 15, and the shaft 5, 10 would not of course turn.

This undesired result is prevented by the interposition of the narrow ring 14 between said members, which holds the two definitely apart, and yet has such a small bearing surface that any tendency of the nut 10 to turn on the shaft is eliminated, and it then performs its function as a stop to prevent similar movement of the handle member. The result therefore is that the 20 shaft 5 is turned, and the member 10 turns with it without moving along said shaft, the pawl 11 offering no resistance to movement of the wheel 10 in that direction.

If however the shaft 5 kicks back, the 25 member 10 is immediately prevented from turning back with the shaft by reason of the pawl 11, the result being that the member 10 is caused to move along the shaft in the only direction which the cut of the threads 30 9 will permit, which is away from the ring 14 and handle portion 15.

This of course effectively breaks the seal or lock between the above named three members, leaving the handle member, which 35 is still grasped by the hand of the operator and thus resists being turned backwards, free to also move along the shaft with the tendency to so move imparted thereto by the backward rotation of the shaft, instead 40 of its turning with the shaft and possibly breaking the arm of the operator.

After such a back-kick, the members 10 and 15 should be retracted to the original 45 positions as described hereinbefore, before again starting cranking operations.

From the foregoing description it will be readily seen that I have produced such a device as substantially fulfills the objects 50 of the invention as set forth herein.

While this specification sets forth in detail the present and preferred construction 55 of the device, still in practice such deviations from such detail may be resorted to as do not form a departure from the spirit of the invention, as defined by the appended claims.

Having thus described my invention, what I claim as new and useful and desire to secure by Letters Patent is:

1. A safety cranking device for gas engines comprising a shaft adapted to be operatively connected to the crank shaft of

the engine, the outer end of said shaft being threaded in the direction of normal rotation thereof, a crank-handle member 65 threaded on to said shaft, a stop member threaded on to the shaft inwardly of the handle member, said stop member being normally positioned to prevent movement of the handle member along the shaft in 70 that direction, and means preventing rotation of the stop member with the shaft other than in the direction of normal rotation of the latter, whereby when a reverse-direction movement is imparted to 75 the shaft the stop will be automatically caused to move along the shaft and away from the handle member.

2. A safety cranking device for gas engines comprising a shaft adapted to be operatively connected to the crankshaft of the engine, the outer end of said shaft being threaded in the direction of normal rotation thereof, a crank-handle member 80 threaded on to said shaft, a stop member threaded on to the shaft inwardly of the handle member, and free to rotate with the shaft only in the direction of normal rotation of the latter, and means on the shaft between the handle and stop member for 85 preventing longitudinal movement of the handle member on the shaft and for preventing the turning of the two together on the shaft.

3. A safety cranking device for gas engines comprising a shaft adapted to be operatively connected to the crankshaft of the engine, the outer end of said shaft being threaded in the direction of normal rotation thereof, a crank-handle member 95 threaded on to said shaft, a stop member threaded on to the shaft inwardly of the handle member, and free to rotate with the shaft only in the direction of normal rotation of the latter, and a spacer ring having relatively small bearing area fitted on the shaft 100 between the stop and handle members.

4. A safety cranking device for gas engines having a shaft adapted to be operatively engaged with the crank-shaft of the 110 engine, comprising a handle member threaded onto said shaft, the threads running in the direction of normal rotation of the shaft, a stop member threaded onto the shaft inwardly of the handle member, 115 ratchet teeth cut in the periphery of said stop member, a fixed pawl engaging the same, and a spacer ring having relatively small bearing area fitted on the shaft between the stop and handle members.

In testimony whereof I affix my signature.

FRANCIS E. TURNER.
